UNITED STATES PATENT OFFICE

172,842

COMBINED WALL PLAQUE AND SHELF

Harry Scheer, Chicago, and Joseph A. Hill, Glen Ellyn, Ill., assignors to Superior Plastics Inc., Chicago, Ill., a corporation of Illinois

Application February 19, 1954, Serial No. 29,106

Term of patent 14 years

(Cl. D29—23)

To all whom it may concern:

Be it known that we, Harry Scheer and Joseph A. Hill, citizens of the United States and residents of Chicago, county of Cook and State of Illinois, and Glen Ellyn, county of Du Page, and State of Illinois, respectively, have invented a new, original, and ornamental Design for a Combined Wall Plaque and Shelf, of which the following is a specification, reference being had to the accompanying drawing, forming a part thereof:

Fig. 1 is a front elevational view of a combined wall plaque and shelf, showing our new design;

Fig. 2 is a top plan view thereof; and

Fig. 3 is a side elevational view thereof.

We claim:

The ornamental design for a combined wall plaque and shelf, substantially as shown.
